United States Patent Office.

ALVAH WASHBURN AND JAMES N. VAN SICKLE, OF MEDINA, OHIO.

Letters Patent No. 65,782, dated June 11, 1867.

IMPROVED MACHINE FOR DRESSING FEATHERS.

The Schedule referred to in these Letters Patent and making part of the same.

TO ALL WHOM IT MAY CONCERN:

Be it known that we, ALVAH WASHBURN and JAMES N. VAN SICKLE, of Medina, in the county of Medina, and State of Ohio, have invented a new and useful Feather-Dressing Machine; and we do hereby declare the following to be a full, clear, and exact description of the same, sufficient to enable one skilled in the art to which the invention appertains to make use of it, reference being had to the accompanying drawings, forming a part of this specification, and in which—

Figure 1 is a side elevation.

Figure 2 is an axial section.

Figure 3 is a transverse section.

In this machine the feathers are treated with steam in a chamber rotating on a horizontal axis; the steam issues in jets into the feathers until they are sufficiently wetted, when it is shut off from the feather-chamber; the ventilators are opened and the feathers are dried by the heat of the steam pipes. The novelty of the invention consists in the arrangements for the induction of steam and the eduction of the water of condensation from the steam pipes. In the drawings—

A is a barrel or other receptacle, mounted by gudgeons upon standards B. One of the journals is hollow, for the passage of steam into the central pipe C, branch pipes D D', and the inside surface of the vessel A. The pressure and consequent heat of the steam is always present in the pipes C D E, but is only admitted into the interior F as it is required. This latter, that is, the suffusion with steam of the interior F, is accomplished by turning the faucets G, which open the connection by pipes M between the pipes E and the perforated pipe H, whence the steam issues in jets into the feathers contained in the receptacle F, as is indicated by red lines in figs. 2 and 3.

The feathers are introduced at the doorway I, and after being subjected to the steam bath for a sufficient time the faucets G are turned off so that the steam no longer issues into the interior. The shutters J are withdrawn so as to expose the perforated panels K which admit the exit of steam, the interior being constantly heated by the steam in the pipes C D E, the machine continuing to revolve and tumbling the feathers over and over as they become gradually dried.

As a means of withdrawing the water of condensation from the pipes C D E, we have so arranged it, as shown in fig. 3, that three of the tubes D project into the central tube C, not into the tubes E, while the other tube, D', does not project into the central tube C, but does project into the tube E, with which it is connected. As the machine revolves, the water in the tube C finds its way through tube D' into tube E', the flanges of the tubes D projecting into C preventing the passage of water into them. The water being thus led into tube E is prevented from flowing back by the projecting flange of the pipe D', and when it has accumulated is withdrawn by means of the faucet L.

Having described our invention, what we claim therein as new, and desire to secure by Letters Patent, is—

The arrangement of the pipes C D E M, faucets G, and perforated pipes H, substantially as described.

We also claim the arrangement shown in fig. 3, whereby, during the rotation of the machine, the water of condensation is led into a single pipe, from which it is discharged by faucet L, substantially as described.

The above specification of our invention signed by us this 13th day of February, 1867.

A. WASHBURN,
J. N. VAN SICKLE.
